MERCURY DOSER

George A. Freeman, East Orange, N. J., and Howard J. Conlin, Fairmont, W. Va., assignors to Westinghouse Electric Corporation, East Pittsburgh, Pa., a corporation of Pennsylvania

Application March 17, 1942, Serial No. 435,020

12 Claims. (Cl. 222—357)

1

This invention relates to electric lamp manufacture, and more particularly to gas charging apparatus, which, in the present embodiment, is specifically a mercury doser for lamps utilizing mercury vapor.

In the electric art which includes not only lamps but also electronic devices, the use of mercury within lamp, tube or other device becomes increasingly prevalent. An outstanding present use is in fluorescent lamps. The amount of mercury required and used in a lamp is dependent upon the size of the lamp, and for some of the smaller lamps the mercury dosage is so small that the usual mechanical valve type of doser introduces too great an error in operation. When it is realized that mercury used in some of the smaller lamps is about the size of an ordinary pin-head, and that mercury exhibits a tenacious surface tension, the difficulty of withdrawing from the body of mercury an assured amount of that minute size each time it is wanted can be appreciated.

An object of the invention is to overcome the insufficiencies of prior art dosers.

A further object is to accurately measure the dosage of mercury.

Another object is to provide means which will accurately measure a minute dosage of mercury.

Yet another object of the invention is to provide a means operable in a vacuum, one that is visual to the operator, and responsive to magnetic control.

Still further objects of the invention will appear to those skilled in the art as the description progresses, both by direct statement thereof and by implication from the context.

In the accompanying drawing, wherein like numerals of reference indicate similar parts throughout the several views, and wherein a preferred physical embodiment of the invention is disclosed by way of example:

Figure 1 is an elevational section of our improved mercury doser;

Figure 2 is a perspective view of the dosing shuttle; and

Figure 3 is a sectional view of said shuttle.

In the specific embodiment of the invention illustrated in said drawing, the reference numeral 10 designates the mercury doser body portion which is preferably a tube of inverted J-shape of which the short leg 11 is closed at its bottom 12 thereby forming a container or reservoir for a mercury supply 13. As this body portion is in an upright position, mercury in the reservoir portion 11 thereof remains therein until intermit-

2

tently removed in operation in minute doses. The body portion provides an interior passage from one leg to the other. The said body portion is furthermore preferably clear glass in order that the quantity and level of mercury may be readily observed, and, as will later appear herein, that the shuttle may be observed.

The long leg 14 of the body portion of the mercury doser is likewise vertical, and below the 10 curved joining upper portion 15 connecting the legs, said long leg provides a shuttle stop 16. A convenient and desirable construction for said stop is obtained by forming a peripheral constriction in the tubular wall of the leg in the 15 vertical portion thereof. By this construction, the stop is next the wall of the tube leaving a central opening through the same. Below this stop 16, a T-branch 17 forms appropriate connection to the vacuum pump (not shown). Still 20 further below, the tube contracts at 18 to appropriately join with the lamp tubulation and lamp bulb 19.

In order to pick up and transfer a measured minute dosage of mercury from the reservoir supply 13 to the lamp, we provide a shuttle 20 detail structure of a preferred form of which is shown in Figures 2 and 3. Said shuttle comprises a disc-like or other head 21 of iron or other material responsive as an armature to an electro 30 or other magnet 22.

Said head is loose within the tubular body portion to an extent permitting passage of mercury therearound, and to keep it approximately normal to the wall of the said body portion wherever situated at the moment, the disc-like head has a guiding tail the specific form of which is of an open character and shown of wire formation. Thus, the tail shown comprises a single piece of wire the end portions 23, 23 whereof are parallel 35 and extend into the disc-like head parallel to the axis thereof. The said end portions of the wire forming the tail are suitably secured in the disc-like head to remain permanently fixed with respect thereto. Furthermore said end portions 40 of the wire are situated quite close to the periphery of the head so as to be close to the walls of the tube in use. The mid-portion of the wire forming the tail is bent into a plane parallel to the disc-like head and provides extended arcuate 45 portions 24, 24 in said plane with radius of curvature substantially equal to that of the head. The arcuate portions are diametrically opposed to each other and at their extremities most distant from the ends of the wire, are joined by a substantially 50 diametrically disposed portion 25 of the wire, 55

This portion 25 of the wire with the arcuate portions 24, 24 together form substantially an S-shape constituting the rear end of the tail and in a plane parallel to the head and transverse to the tube wall wherever situated therein. The tail functions to keep the head from turning askew, keeping it in its intended normal position to the tube wall.

At the forward side of the shuttle head is a measuring cavity 26 for reception of the mercury. As shown, the cavity is formed by drilling an axially central hole through the head and refilling the hole in part with a plug 27 of appropriate length to permit the plug to be flush at the back of the head and depressed the necessary amount at the forward side of the head to form the bottom of said cavity.

In use, the shuttle is arranged to have the forward face and cavity directed upward when the shuttle is in the mercury. By virtue of the relative lightness of the shuttle compared to the specific gravity of mercury, the shuttle will float at the top of the mercury as shown in Fig. 1. By manipulation of the magnet 22, which is preferably an electro-magnet, in proximity to the head 21 and in a downward direction, the head is caused to submerge and a globule of mercury then enters the cavity 26 where it remains when the electromagnet is moved upward again. Movement of the magnet is caused to follow the curvature of the tubular body portion which thereby brings the shuttle to an upside down position above the constriction of stop 16. The magnet is withdrawn laterally, permitting the shuttle to drop the result of which is to thump the shuttle against the stop and cause discharge of the globule of mercury from the cavity. Thereupon the mercury falls down the passageway through the stop and remainder of the tubing into the lamp.

In order to promote the entry of the mercury into the cavity 26 of the shuttle when the shuttle is submerged in the mercury, the bottom of the cavity is preferably mercury plated, as by applying a "strike" bath of mercurous nitrate and nitric acid thereto. The mercury plating will cause a drop of mercury to stick in the cavity sufficiently to overcome surface tension of the mercury pool that tends to pull the drop out of the cavity. A single dipping of the shuttle thus will definitely measure and bring up for delivery the desired amount of mercury to charge the lamp.

Since the various details of construction and steps involved in the method, as well as the precise relation and functioning of parts are subject to variation and change without departing from the inventive concept or scope of the invention, it is intended that all matter contained in the specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

We claim:

1. A mercury doser comprising a body portion formed with a passageway of substantially uniform cross-section throughout its length having a curved portion and at opposite ends thereof having depending portions one of said depending portions being closed at the bottom and constitut-

ing a mercury reservoir, and means slidable in said passageway from upwardly directed position in the mercury reservoir portion thereof to an inverted position in another depending portion 5 of said passageway for picking up and discharging mercury doses.

2. A mercury doser comprising an inverted J-shaped body portion formed with a passageway of which the cross-section is substantially uniform throughout the length thereof and of which the short leg constitutes a reservoir and the long leg constitutes a discharge passage, and means slidable lengthwise of and guided by said passageway by virtue of said uniform cross-section there- 15 of for picking up mercury in the reservoir leg and discharging the mercury in the discharge passage upon transfer of said means into said discharge passage.

3. A mercury doser comprising a body portion 20 having an inverting passageway one part whereof constitutes a vertically upright mercury reservoir and another part constitutes a vertically downward discharge passage, and a shuttle loosely slidable in said passageway and adapted to be 25 submerged in the mercury, the upper side of the shuttle having a cavity therein for receiving a mercury dose, said cavity having mercury plating therein for overcoming effects of surface tension of the pool mercury tending to extract the 30 mercury from the cavity, and said shuttle being movable to an upside down position in the discharge passage with said cavity then directed vertically downward for discharge of the dose of mercury therein.

4. A mercury doser comprising an invertable 35 mercury-transfer means having a small cavity for reception and temporary retention of a mercury dose, said cavity adapted to be filled by dipping the transfer means into a mercury pool, and means in said cavity tending to counteract effect 40 of surface tension of departing mercury from adjacent the cavity as said transfer means comes to the surface of the mercury pool at completion of the dipping thereinto.

5. A mercury doser comprising an invertable 45 mercury-transfer means having a small cavity for reception and temporary retention of a mercury dose, means providing a vertical passage receiving the mercury-transfer means in inverted 50 position for gravitation thereof downward, and annular means within said passage at a lower part thereof constituting a stop for said mercury-transfer means for jarring the dose of mercury out of the orifice in transferring and delivering the said dose.

6. A mercury doser comprising a container for 55 a pool of mercury, pick up and transfer means in said container adapted to dip into the mercury and pick up a drop thereof, said container having a passage one part whereof is inverted with respect to another part and both parts forming a passageway for said means for guiding movement of said means to an inverted position for discharge of the said drop, and a movable magnet exterior to said container effective on said means for dipping said means into the mercury and for transferring said means back and forth in said passage.

7. A mercury doser comprising a body portion 70 formed with a passageway having a curved portion and at opposite ends thereof having depending portions, one of said depending portions being closed at the bottom and constituting a mercury reservoir, means slidable in said passageway 75 from upwardly directed position in the mercury

reservoir portion thereof to an inverted position in another portion of said passageway for picking up and discharging mercury doses, and an external magnet movable in parallelism to the said passageway and effective on said means for moving the same back and forth in the passageway from one portion thereof to another.

8. A mercury doser comprising an inverted J-shaped body portion of which the short leg constitutes a reservoir and the long leg constitutes a discharge passage, means in said body portion transferable from within one leg thereof to the other and free of external mechanical attachment for picking up mercury in the reservoir leg and discharging the mercury in the discharge passage upon transfer of said means into said discharge passage, and external electro-magnetic means movable contiguous to and along said body portion and effective on said means in the body portion to move the same correspondingly within the body portion as the said electro-magnetic means moves longitudinally at the exterior of the body portion.

9. A mercury doser comprising a body portion having an inverting passageway one part whereof constitutes a mercury reservoir and another part constitutes a discharge passage, a shuttle transferable from within one leg of the body portion to the other and free of external mechanical attachment and loosely slideable in said passageway and adapted to be submerged in the mercury right side up and thereby receive a dose of mercury, said shuttle being movable to an upside down position in the discharge passage for discharge of the dose of mercury received from the reservoir, and magnetic means outside the body portion and effective therethrough on said shuttle for operating the shuttle from submerged position to upside down position and back again.

10. A mercury doser comprising a body portion formed with a passageway having a curved portion and at opposite ends thereof having depending portions, one of said depending portions being closed at the bottom and constituting a mercury reservoir, a shuttle slideable in said passageway from upwardly directed position in the mercury reservoir portion thereof to an inverted position in another portion of said passageway, said shuttle having means adapted to receive and retain a dose of mercury while the shuttle is upright in the reservoir portion of the passageway and to carry said dose of mercury as the shuttle passes to the other depending portion of the passageway, and an external magnet movable adjacent said passageway and effective on said shuttle for moving the same back and forth in the passageway from one portion thereof to another, whereby a dose of mercury may be picked up in one portion of the passageway and transferred free from the mercury in the reservoir by said shuttle and discharged in another position of the passageway.

11. A mercury doser comprising a body portion formed with a passageway having a curved portion and at opposite ends thereof having depending portions, one of said depending portions being closed at the bottom and constituting a mercury reservoir, a shuttle slideable in said passageway from upwardly directed position in the mercury reservoir portion thereof to an inverted position in another portion of said passageway, said shuttle having a head and a tail by which the shuttle is guided longitudinally of said passageway and said shuttle having means adapted to receive and retain a dose of mercury while the shuttle is upright in the reservoir portion of the passageway and to carry said dose of mercury as the shuttle passes to the other depending portion of the passageway, and an external magnet movable adjacent said passageway and effective on said shuttle for moving the same back and forth in the passageway from one portion thereof to another, whereby a dose of mercury may be picked up in one portion of the passageway and transferred free from the mercury in the reservoir by said shuttle and discharged in another position of the passageway.

12. A mercury doser comprising a body portion having a hermetically closable passageway of substantially uniform cross-section throughout its length, said passageway having one part thereof vertically upright and closed at its bottom for constituting a mercury reservoir and having another part extending vertically downward for constituting a discharge passage, said passageway having an intermediate and uppermost part thereof curved downwardly and in connecting parts, and a magnetic cup transfer mechanism loosely slideable in said passageway and in all of said parts of said passageway and constructed and arranged to be submerged in the mercury, the upper side of the cup transfer mechanism having a cavity therein for receiving a mercury dose, and said cup transfer mechanism being movable from an upright position in said reservoir and through said passageway to an upside down position in the discharge passage with said cavity then directed vertically downward for discharge of the dose of mercury therein.
